UNITED STATES PATENT OFFICE.

CLINTON C. MURPHY, OF CHICAGO, ILLINOIS.

METAL CAR-ROOF.

1,140,842.

Specification of Letters Patent. Patented May 25, 1915.

Application filed October 16, 1912. Serial No. 724,852.

To all whom it may concern:

Be it known that I, CLINTON C. MURPHY, a citizen of the United States, residing at Chicago, in the county of Cook and State 5 of Illinois, have invented certain new and useful Improvements in Metal Car-Roofs, of which the following is a specification.

My invention relates to the construction 10 of railway cars, and particularly the roofs of railway box or house cars.

The invention consists in certain novel and improved constructions, arrangements and devices whereby a roof is provided which is very strong, light, durable, water- 15 proof, inexpensive to build, and which will effectively brace the car structure against the stresses to which it is subjected in service and particularly against those stresses which tend to cause the car to weave.

20 The invention, furthermore, provides a novel roof construction for railway cars composed entirely, or very largely, of metal and consisting, to a large extent, of common and simple structural elements which can 25 either be purchased in the open market or readily made from stock so obtainable and which, furthermore, can be assembled with convenience and relatively small expense.

The invention consists further in the several 30 novel constructions, arrangements and devices, taken singly and in combination, relating to car roof structures shown in the drawings annexed hereto and which will be hereinafter described and claimed.

35 The invention is illustrated, in a preferred embodiment, in the accompanying drawings wherein—

Figure 1 is a plan view of one end of a 40 railway box car, the roof sheets, carline caps and running boards being removed at the right hand side of the figure in order to show the structures underneath them; Fig. 2, a side elevation of the parts shown in Fig. 1; Fig. 3, a cross sectional view, on an 45 enlarged scale, taken on line 3—3 of Fig. 1, looking in the direction of arrows; Fig. 4, a sectional view on line 4—4 of Fig. 3, looking in the direction of the arrows; Fig. 5, an enlarged sectional view taken on line 50 5—5 of Fig. 2, looking in the direction of the arrows; Fig. 6, an end elevation of the carline cap and neighboring structures; Fig. 7, a fragmentary view, in perspective, of one of the roof sheets; Fig. 8, a similar view

of one of the carline caps, and Fig. 9, a fragmentary sectional plan of the lower portion of the depending web of one of the carlines illustrating the manner in which the diagonal tension rods are engaged with the carlines. 55

Like characters of reference designate like parts in the several figures of the drawings.

Referring to the drawings, 25 designates the carlines, each of which consists of a channel member open at the top and formed 60 preferably with the depending web 26. The latter is preferably shorter than the rest of the carline and the projecting ends of the carline rest upon the side plates 27 as best shown in Fig. 5. The carlines are held in 65 place on the side plates preferably by means of the angular gussets 28 riveted to the depending flanges 26 and secured to the side wall structure of the car by bolts 29 which pass through the side plates 27. 75

The ridge pole, or element which most nearly corresponds to the ridge pole of the car roof, consists preferably of a tension member or rod 30 which preferably extends from end to end of the car passing through 80 openings in the webs 26 of the several carlines and is anchored to the opposite ends of the car in the manner indicated at the left hand side of Fig. 1.

Surrounding the tension member 30 are 85 the spacing sleeves 31 which intervene between the depending flanges 26 of the carlines and are compressed when the ridge pole member 30 is put under tension.

Preferably the roof structure is further 90 reinforced and strengthened by means of a number of diagonally arranged tension rods 32 which connect the several carlines together. In the preferred arrangement which is best shown in Fig. 1, a pair of 95 these rods extend from points near the middle of each carline to the ends of the carlines adjacent thereto, the rods passing through perforations in the webs 26 and through the obliquely faced washers 33 and 100 being provided with nuts 34 (Fig. 9).

It will be seen that the structure as above described will be very strong and at the same time light. It is very well calculated to prevent the car from being racked and 105 the parts thereof loosened by the stresses commonly known as weaving stresses to which railway box cars are subjected when

in service. The tendency of box cars to weave constitutes one of the most common causes operating to shorten the life of these structures. It will be noted also that this construction, by binding the end and side walls of the car together tends to check the bulging of these walls. The roof structure throughout is a tension structure. The tension rods 32 bind all of the parts of the roof one to another. A stress on one part of the roof is transmitted to the whole structure. For this reason the roof of my invention is particularly well calculated to withstand the constant vibrations to which all the parts of a railway car are subjected when in use. When the parts of the ordinary car roof have become a little loose the looseness increases very rapidly due to the vibration to which the car is subjected, with the result that the car soon becomes racked and out of shape so that it is impossible to effectively repair it.

Between each carline is a roof sheet 35 formed on its transverse edges with the inner vertex U-shaped flanges 36 (Fig. 7) which extend over the upstanding webs 37 of the carlines. The engagement of the roof sheets with the carlines is preferably a loose engagement as shown so that some play is permitted at these places which will prevent the rupture of the roof sheets in the event the car weaves. Some weaving is inevitable no matter how strong and rigid the roof structure may be.

The carlines, and the overlapping edges of the roof sheets, are covered by carline caps 38 (Fig. 8) which are preferably sheet metal channel members provided with end pieces 39 overlapping the side fascia plates 40 of the car. The caps are held in place by bolts 41, or other suitable fastening devices, which pass through the fascia plates 40 and the side sheathing of the car 42. The end pieces 39 of the caps overlap the edges of flanges 43 on the ends of the roof sheets. This holds the roof sheets in position but without preventing them from shifting a trifle, if the roof is strained so as to require it. The end pieces 39 are formed with openings 44 at the level of the bottom of the channeled portions of the carlines, the purpose of these openings being to allow the escape of any water which may work in through the channels. The openings are preferably made by slitting or punching the ends of the cap and bending the intervening metal out so as to form lips 44a which serve to prevent rain, dust, and the like, from entering the openings. The running board 45 is supported on the saddles 46 preferably made of wood which fit over the carlines and are secured thereto by T bolts 47 (Fig. 4), the transverse members of which extend through and are secured to the upstanding webs 37 of the carlines. The roof sheets are

formed at their inner edges with the notches 48 so that they may be placed in position after the T bolts have been secured to the carlines.

It will be seen that this arrangement of carlines and roof sheets gives a roof which is at once light, simple, waterproof and, to a certain extent, flexible. By bending the edges of the roof sheets up over the upstanding webs 37 of the carlines and covering the carlines with the caps 38 the connection between the roof sheets and carlines is perfectly waterproof. If any water should work in between the roof sheets and the cap it will be drained out through the openings 44.

While I have described my invention in certain preferred embodiments, it will be understood that some modification might be made in the form, construction and arrangement of the parts without departure from the invention. Therefore I do not wish to be understood as limiting the invention to the exact particulars shown and described.

I claim:

1. In a roof structure for railway cars, the combination with a plurality of carlines, of a plurality of diagonally arranged tension members connecting said carlines one with another, and a tension member running longitudinally of the car along the center line of the roof structure. 90
2. In a roof structure for railway cars, the combination with a plurality of carlines provided with a depending web having apertures therein, of a plurality of diagonally arranged tension members consisting of rods having their ends threaded and extending through said apertures so as to connect said carlines one with another, a tension member running longitudinally of the car along the center line of the roof structure, and spacing sleeves on said tension member arranged between said carlines. 95
3. In a roof structure for railway cars, the combination with a plurality of carlines, of a plurality of diagonally arranged tension members connecting the ends of each carline with the middle of the next adjacent carline, a tension member running longitudinally of the roof structure from end to end of the car, and compression members arranged between the carlines. 100
4. In a roof structure for railway cars, the combination with a plurality of metal carlines formed with depending webs, diagonally arranged tension rods connecting the webs of said carlines, a tension member extending from end to end of the car along the center line of the car and through said webs, and spacing sleeves on said tension member. 105
5. In a roof structure for railway cars, the combination with a plurality of carlines consisting of channeled members open at 110

the top, of roof sheets, the edges of which are bent so as to extend into the channels of said carlines, running board saddles arranged to stand over the carlines, and 5 bolts secured to the upright webs of the channels of the carlines and through said saddles, the edges of the roof sheets being formed with notches, for the purpose described.

CLINTON C. MURPHY.
